UNITED STATES PATENT OFFICE.

JOHN J. C. SMITH, OF PASSAIC, NEW JERSEY, ASSIGNOR TO PAUL M. HAMMALIAN, OF HACKENSACK, NEW JERSEY.

APPARATUS FOR MAKING STEREOTYPES.

965,241.

Specification of Letters Patent. Patented July 26, 1910.

Application filed April 1, 1909. Serial No. 487,169.

To all whom it may concern:

Be it known that I, JOHN J. C. SMITH, a citizen of the United States, and residing at Passaic, county of Passaic, State of New Jersey, have invented new and useful Improvements in Apparatus for Making Stereotypes; and in order that those skilled in the art may understand, make, and use my invention I give the following specification, reference being had to the accompanying drawings, forming part thereof.

My invention relates generally to the production of cast metal designs but more particularly to making of new and improved stereotypes for the reproduction by ordinary printing processes of cuts, illustrations, designs, type-matter and the like.

The invention has for its objects the production of stereotypes of special and superior material to that at present generally used; the provision of improved molds and molding apparatus for the making and casting of stereotypes, and the saving of time required to produce stereotypes.

Stereotypes at present employed are formed, either by casting type-metal against a matrix of papier mâché, or by electrotyping on a wax or similar impression, the electrotype shell being afterward reinforced or backed by type-metal. A great desideratum in the art of making stereotypes has been to produce a stereotype of harder metal than the type-metal or electrotype plates commonly used, which are heavy in weight and soon become defaced by wear and usage. Further, since it is desired to reproduce cuts, illustrations, type-matter and the like in many different publications in different and remote places and at as nearly the same time as possible, the cost of transportation, particularly where sent by mail, as is frequently done, is, owing to the weight of the ordinary type-metal stereotypes, an item of considerable expense which my invention is intended to overcome. The employment of other metals than type-metals has hitherto been prohibited by the fact that harder and lighter metals suitable for printing purposes require considerably higher temperature for melting, making the use of a papier mâché matrix impossible and necessitating the employment of a refractory material for the same. In employing a mold or matrix of refractory material, however, further dif-

sulty is encountered in that such molds are formed of the molding material in a plastic or semi-fluid state from which it has to dry and harden, and this drying, in order to be sufficiently rapid, requires a heat of about 600° F. Under these conditions fine or even large cracks make their appearance in ordinary molds. It will be obvious that even the finest cracks, or a slight amount of shrinking or warping will destroy the mold, particularly when it is considered that the metal is cast in the molds under pressure, as it is contemplated with the molds of my present invention.

I am aware that plaster molds have been employed for producing metal castings and stereotypes, but such molds as have heretofore been used have the disadvantage not only of not satisfying the above requirements, but of requiring such length of time to dry them by heat that their use for making stereotypes is out of the question, because stereotypes are required to be finished on very short notice, sometimes no more than three or four hours,—a period insufficient even to dry the ordinary plaster mold.

Still a further difficulty to be overcome with molds of such material is that the material of the mold must be capable of entering the finest lines of a delicate or intricate design and of taking and retaining impression in a high degree of perfection, and also that it must be capable of withdrawal from the pattern without distortion and must separate from the pattern perfectly and clearly.

In the accompanying drawings Figure 1 is an underside view of a mold plate. Fig. 2 is a longitudinal view of Fig. 1. Fig. 3 is a plan view of the base-board with patterns and gate or sprue blocks in position. Fig. 3^a is a detail sectional view of a modification on enlarged scale. Fig. 4 is a plan view representing a mold plate and base-board arranged for molding, with part of the mold plate broken away to show the patterns and gate blocks in position. Fig. 5 is a longitudinal sectional view of Fig. 4. Fig. 6 is a similar view to Fig. 5, showing the mold partially raised off the patterns. Fig. 7 is a view of the underside or interior of the formed mold. Fig. 8 is a plan view of a separating plate forming part of the apparatus used in casting. Fig. 9 is a longitudinal sectional view of Fig. 8. Fig. 10 is a

longitudinal sectional view of two molds with a separating plate between, arranged upon a platform of a casting machine.

The apparatus for forming the molds 5 comprises a frame 1 formed of a metal plate 2 of any desired or suitable size—say 16" by 20" or larger—easily handled and accommodated in the casting machine. This casting machine will be hereinafter referred 10 to, but forms no part of my present invention. The plate 2 is preferably of steel as affording the requisite strength and stiffness, and also because the mold composition adheres well to steel. Other metals or alloys, 15 brass, for example, may be employed for this plate if desired. This plate 2 is foraminated or perforated to provide openings or holes 3, the purpose of which will herein-after appear. These holes may be tapered 20 as illustrated in Fig. 3^a, if desired, so as to give the mold composition a better grip to the frame. This will be desirable where other metals than steel are employed for the frame 1. Plate 2 is also provided with a 25 rim or flange 4 around its edge on one side thereof and secured thereto in any convenient manner, as by riveting, brazing or the like. On one side the rim is interrupted, as at 5, forming an opening or gate for use 30 during the casting operation. This opening 5 is closed, however, in the process of forming the mold, by means of a removable block 6, (see Fig. 4) or in any other convenient manner. The perforated plate 2 with its 35 rim or flange 4 forms a frame 1, relatively shallow so as to take very little molding material, and so form a thin mold, the strength and rigidity of which is derived from the metallic frame. The frames I have em- 40 ployed are not over three-eighths of an inch in thickness, including the plate 2. At each corner the frame is provided with a thumb-screw 7 passing through a threaded opening 7^a therein.

45 For use with the frames 1 I provide a base 8 of somewhat greater dimensions than the frame. This base may be of wood or any suitable material, or may form the top of a table or work bench. On its upper sur- 50 face this base is provided with a non-adhesive surface to which the molding material will not stick, as, for example, a smooth rubber sheet 9.

The manner of using the apparatus above 55 described and the process of preparing a mold is as follows:

I take the pattern or patterns P P of which it is desired to make a stereotype or casting and fasten the same temporarily on the base 8 60 by means of brads, or in any other convenient manner. (See Fig. 3). One or a number of such patterns may be so secured in place, as may be desired, and according to the dimensions of the mold frame employed.

65 In the drawings I have shown two patterns,

by way of example. The patterns will be arranged with sufficient space between them to allow for the necessary gates or sprues, as will be understood by any one skilled in the molding or casting art. These gates or 70 sprues are formed by removably fastening to the base 8 blocks or pieces 10 of suitable shape, and of a thickness slightly greater than the patterns, but of less thickness than the depth of the mold frame 1 (see Fig. 5). 75 Having arranged the patterns and the blocks or plates forming the gate and sprues as above specified, I coat the faces thereof with a thin film of separating medium to insure a clean separation of the mold from the patterns. For this purpose I preferably employ good sperm oil, applied to the surface of the patterns with a stiff brush so as to reach and coat every cavity and deep line of the pattern. This coating of oil or the like, 80 while necessary to insure clean separation of mold from patterns, has the disadvantage of increasing the tendency of air to become confined in the cavities and lines of the design, thereby preventing the plaster compo- 85 sition from entering and thus producing a defective mold. The repellent or antagonistic character of the oiled surface against the water of the fluid plaster composition tends to keep the latter from flowing into 90 and occupying the deeper recesses and lines of the pattern. It will be understood that for stereotypes the design or pattern is fine and intricate, presenting many hundreds of small recesses and cavities on a surface less 95 than fifty square inches, and in order to produce a successful stereotype a faithful reproduction of every line and cavity of the design is required. Agitation of the plaster composition, after it has been cast upon 100 the pattern and while still fluid, has been proposed, but this is only effective in designs which do not present the intricacies of detail possessed by stereotypes and is in- 105 effective for such moldings. Furthermore, 110 if agitation be attempted for the purpose of removing the confined air in the cavities, as, for instance, by applying a brush to drive the same out, the oil film becomes re- 115 moved in places where reached by the brush, and this results in the mold composition sticking to the pattern and producing de- 120 fects. To overcome these difficulties I wet or moisten the oiled surface of the pattern with a fluid which will lie uniformly there- 125 on and not be either repellent or antagonistic to the water of the molding composition. For such fluid I have found wood alcohol to give good and satisfactory results. Having therefore coated the patterns with oil, 130 as above stated, I then apply wood alcohol to the oiled surface. This is preferably done by applying the wood alcohol in a fine spray by means of an atomizer. Care should be taken to apply no more alcohol 135

than is required to wet the oiled surface, as an excess of alcohol would be likely to delay the setting or hardening of the mold. The mold frame is then placed over the prepared patterns and the same is held in position either by arranging weights around its edges or by clamping it to the base, or in any convenient way.

The molding composition having been prepared, is now poured into the mold or frame through the openings 3. This molding composition must possess the requisite characteristics of withstanding the heat of the molten metal to be cast therein when the mold is formed without checking or cracking, since the finest crack would be reproduced on the cast stereotype. This heat will be about 900° F. The molding composition must possess such tenacity that it will, when set, withdraw absolutely clean from the patterns and without distortion. And further it must be of such character that it will enter the finest detail and lines of the design and reproduce a sharp and perfect impression. I have invented a molding composition possessing these characteristics and have filed an application for Letters Patent therefor of even date herewith, said application having Serial No. 487,168 filed April 1, 1909. As disclosure of this molding composition is not requisite to the understanding and carrying out of the present invention, further reference thereto is not believed to be necessary. Sufficient of the molding composition is poured in to completely fill the interior of the mold frame and to rise through the openings 3 and overflow the same. When the composition has partially set, say in about ten minutes, the surplus composition is removed by striking it off, by means of a stick or bar, level with the top or outer face of plate 2. This leaves the composition filling the holes or openings 3, as shown in Figs. 5 and 6 in which the molding composition is represented at M. After about ten minutes more, the composition sets sufficiently hard to permit the mold to be removed from the base-board and patterns. This removal of the mold requires great care: To enable the removing of the mold to be accomplished with certainty, and without damage, I have provided at each corner of the mold plate the thumb-screws 7. By turning each of these screws slightly in succession and to a similar degree, the mold will be lifted from the base-board without any danger of defacing the molded impression, as is clearly illustrated in Fig. 6. The mold may now be placed at once into the drying oven. This oven may be of any suitable kind, heated by gas or other means of heat, to a temperature of about 600° F. The molds sustain this degree of heat without any danger of cracking or any other injury. They are left in the oven for

a period of from two to three hours, at the end of which time the moisture and water are all expelled therefrom. The numerous perforations or openings 3 in the mold plate permit ready escape of the moisture and water; and by reason of the fact that the mold material itself, consists of only a thin layer of the molding composition, the time required for drying is reduced to a minimum. After having been dried the molds are ready for the casting operation. It will be apparent that the mold is constituted by the thin layer of molding composition which carries the design or impression, together with the perforated mold frame or plate 2. The latter gives great stiffness, rigidity and strength to the mold, not only protecting it from damage but enabling it to resist the pressure to which it is subjected in the casting operation.

I have contemplated employing molds prepared in the manner above described in machines or apparatus for casting metal under pressure. Machines or apparatus of this type have long been known, and have been invented by myself and others. (See for instance United States Patents, No. 70,038 granted to Michael Smith, October 22 1867, and No. 477,231 granted to myself and Victor E. Smith June 21, 1892, No. 591,430, granted to me October 12, 1897. In machines of this character the fluid metal is forced into the molds under what is substantially the equivalent of hydraulic pressure, which forces the metal into the fine details and lines of the designs, enabling, thereby, a perfect casting to be obtained.

In using the molds in the casting operation I employ a separating plate, illustrated in Figs. 8 and 9 by the numeral 11. This plate is similar to the mold plate 2, in that it is provided with perforations or openings 12, similar to the openings 3 of plate 2, and is also stiffened by a rim or flange, 13, around its edges. In this case, however, the rim or flange 13 is on both sides of the plate 11 as shown in Figs. 9 and 10. This separating plate 11 is prepared by placing it on a base-board and pouring the molding composition through the openings 12 until the composition rises to the level of the upper face of the rim 13, when it is evened off. The result is a plate, as illustrated in Fig. 9, having a central metallic plate 11 with the molding compositions 14 on each side thereof flush with the rim.

In arranging the molds in a casting machine a number of molds may be taken and arranged in pairs, face to face, as illustrated in Fig. 10, with the plate 11 intermediate the open face of adjacent molds. Only one pair of molds with the intermediate plate 11, is shown in Fig. 10 on the platform 14 of molding machine; but it will be understood that any convenient number of molds

1 may be so arranged with a plate 11 between the open faces of each pair. The gates 5 of the molds are arranged to come all in registry with the outlet from the mol-
 5 ten metal receptacle (not shown) of the casting machine. As illustrated in Fig. 10, the gates of the mold are at the right, in registry with a suitable opening or passage-
 10 way 15 in the casting machine. When the desired number of molds have been arranged in the casting machine they are clamped together under heavy pressure, as will be understood by those skilled in operating such machines. The casting machine is then
 15 operated to force the molten metal through the gates into the molds.

It will be noted that by having the molds and the intermediate plate of the construction described they are not only of sufficient strength to resist the pressure to which they are subjected, but, what is an important consideration, the gases from the molten metal, and also the air in the casting spaces, find exit through the porous molding com-
 20 position filling the holes in the said plates. It will be understood that the molding composition is of a finely porous character, permeable to gases, particularly under the pressure of the metal forced into the mold.
 25

30 By reason of the above described improvements I am enabled to produce, in a short space of time, perfect castings of stereotypes, of a fineness and perfection of design which is only attained, so far as I am aware, 35 by the electrotype process, and also to produce such castings within as short or shorter a time than now required for making electrotype plates. The molding composition which I employ, of which the mold is made, 40 is such as to permit the same to be exposed at once to the high degree of heat required to dry it in a short time without cracking or injury to the finest detail thereof. The perforated plate or frame forming part of the mold
 45 not only gives the rigidity and strength required, by reason of openings 3, but does not interfere with the rapidity of drying, and at the same time eliminates the difficulty usually encountered of occluded gases and
 50 air in the molds when casting. The mold plate forming a part of the mold also enables the mold to be very thin, thereby economizing material, as well as the time required for drying the same.
 55 While I have illustrated and described a particular form of apparatus and mode of operation, it will be understood that this is by way of illustration only, and not of limitation to the precise details and steps dis-
 60 closed, since it will be obvious that various modifications may be made by those skilled in the art, without departing from the invention.

Matters shown and described in the fore-
 65 going specification but not especially

claimed herein form the subject matter of a divisional application, Ser. No. 518,319, filed September 18, 1909.

What I claim is:

1. In apparatus for making molds, a frame 70 having sides to inclose the molding space and patterns, and a plate supported by said sides and extending over the space inclosed thereby, said plate provided with a plurality of apertures or perforations through 75 which fluid molding material may be poured or cast on the patterns inclosed by said frame and fill said apertures whereby said frame becomes partially embedded in and forms part of the mold produced. 80

2. In apparatus for making molds, a frame for forming the mold space about the patterns, said frame having a top plate pro-
 85 vided with a plurality of holes and uniting with the mold produced to form a part thereof, and means for gradually and evenly lifting said frame and mold from the patterns.

3. In apparatus for making molds, a frame for forming the mold space about the pat- 90 terns, said frame having a top plate pro-
 vided with a plurality of holes and uniting with the mold produced to form a part thereof, and lifting screws on said frame for raising the same from the patterns. 95

4. A frame for making molds, said frame open at the bottom, having sides slightly higher than the height of the patterns to be molded, and a top plate having a plurality of perforations therein to permit the 100 pouring of the molding material therethrough and the escape of surplus molding material.

5. Molding apparatus comprising a base, a non-adhesive surface on said base, and a 105 molding frame adapted to rest on said base, said frame open at the bottom and having a perforated top plate.

6. Molding apparatus comprising a base for supporting the patterns to be molded, a 110 frame surrounding said patterns and having a perforated top plate, and lifting screws for said frame threaded therethrough and bearing upon said base.

7. A mold for forming castings, said 115 molds formed of a set molding material, and a metallic frame supporting said mold-
 ing material and forming part of the mold.

8. A mold for forming castings, said mold comprising a metallic frame or support hav- 120 ing a mold of plaster composition cast and set therein, said frame forming part of the mold.

9. A mold for forming castings, said mold comprising a set and hardened hydrated 125 molding material bearing the design to be cast, and a metallic frame partially em-
 bedded in said molding material.

10. A mold for forming castings, said mold comprising a set and hardened hy- 130

drated molding material bearing the design to be cast, a metallic frame surrounding said molding material on the sides and back, the back of said frame consisting of a plate 5 having perforations therethrough, with the molding material filling said perforations.

11. A mold for forming castings, said mold comprising a metallic frame having shallow sides and a perforated back or bottom plate, a set and hardened porous molding material, bearing the design to be cast, on said mold said material filling the perforations in said bottom or back plate.

12. A mold for forming castings, said mold comprising a refractory molding material bearing the design, said molding material having partially embedded therein a metallic plate provided with perforations and a rim on said plate and surrounding 20 said molding material.

13. In molding apparatus, a base or supporting plate for the molds, said supporting plate comprising a metallic plate provided with perforations, a flange or rim around the sides of said plate and projecting from both sides thereof, and a set and hardened refractory molding material on both sides of said plate and even with the rim thereof. 25

14. In molding apparatus a base or supporting plate for the molds, said plate formed of a refractory, porous molding material, and a perforated metallic plate embedded therein, and a rim surrounding said plate and molding material. 30
